PORTABLE HOIST AND LOAD
TRANSPORTING DEVICE

Richard A. Wallace, Hagerstown, Md.

Application May 16, 1947, Serial No. 748,457

12 Claims. (Cl. 254—139.1)

1

This invention relates to improvements in a portable crane or hoist.

A principal object of the invention is the provision of a portable crane of a generally improved and simplified construction over prior devices of this kind thereby adapting the crane to the handling of objects over a greater range and with greater ease and convenience and with the expenditure of less time and effort.

A further and important object of the invention is the provision of a portable crane embodying a base of channel iron construction, a mast of I-beam construction rising from the base, and a boom of channel iron construction supported by the mast whereby the crane is relatively light in weight and thus easily transported to and from different operative positions, while on the other hand, crane is strong and capable of withstanding substantial weight in the lifting operations thereof.

A still further object of the invention is the provision of a portable crane embodying a caster supported base, a mast extending vertically from one end of the base and a boom slidably supported at one end thereof on the mast for vertical adjustment thereon to different operative positions upwardly from a point adjacent the base, a windlass supported by the mast, and a cable extending from a drum on the windlass successively over pulleys on the mast and boom and supporting a hook at its free end depending beneath the free end of the boom, the base being of substantially greater length than the boom for positioning of the free end portion thereof beneath an object to be lifted and handled by the boom.

A still further object of the invention is the provision of a portable crane embodying an elongated caster supported base and a windlass operated lifting hook disposed above the base in spaced relation to an end thereof, and the base being provided with a removable support beneath the hook whereby an object may be lifted by the hook and lowered onto the removable support, and the object then conveyed to a desired point through movement of the caster supported base.

A still further object of the invention is the provision of a portable crane including a base, a mast, and a boom slidable on the mast and supported thereby at desired predetermined positions above the base, a windlass operated cable extending from the mast along the boom to depend from the free end thereof for movement relative thereto, and the cable being provided with a hook on its free end adapted to engage the boom to arrest relative movement between the cable and boom whereby the boom will move with the cable upon further operation of the windlass.

2

A still further object of the invention is the provision of a portable crane including a base, a mast, and a boom slidably supported on the mast, a windlass operated cable extending along the boom and movable relatively thereto, and clamp means for selectively locking the cable to the boom for movement of the boom along the mast upon movement of the cable.

A still further object of the invention is the provision of a portable crane including a base, a mast extending vertically from the base and a boom having one end thereof slidably supported on the mast, wherein provision is made for selectively holding the boom in successive vertical adjusted positions on the mast and for permitting the boom to descend on the mast, and wherein the boom is free to rise on the mast, either when engaged by the cable hook or when the cable is locked by the clamp means.

20 Other objects and advantages of the invention will become apparent in the course of the following disclosure:

Fig. 1 is a side elevational view of the improved crane, with the boom thereof in an intermediate position on the mast and the windlass operated cable depending fully from the free end of the boom, an upper extreme position of the boom being illustrated in dot-and-dash lines;

Fig. 2 is an enlarged section in the plane of line 2—2, Fig. 1;

Fig. 3 is a rear elevational view of the crane of Fig. 1;

Fig. 4 is a front elevational view of the crane with the parts in the full-line position of Fig. 1;

35 Fig. 5 is an enlarged vertical sectional view in the plane of line 5—5, Fig. 1;

Fig. 6 is a top plan view of the crane showing the supporting base and relation of the boom thereto;

40 Fig. 7 is a side elevational view on a substantially enlarged scale, of a combined cable clamp and boom retaining means forming one of the structural features of my improved crane, the view being partially in section;

45 Fig. 8 is a right hand end elevational of the structure as illustrated in Fig. 7 and showing a section of the boom with which it is operatively associated.

Referring now in detail to the drawings, and 50 first to Figs. 1, 3, 4 and 6, the improved portable crane comprises a base 10, a mast or upright 11 and a relatively movable lifting boom 12. The base 10 and mast 11, as shown, are a unitary rigid structure while the boom 12 is slidably supported on the mast for vertical movement relative to the base.

An important feature of the invention is in the structures of the base, mast and boom, which constitute the major elements of the crane, so 55 that the device will be relatively light in weight.

while possessing maximum strength. Accordingly, the base 10 and boom 12 are formed of joined channel sections whereas the mast 11 is an I-section beam 15. The base 10 comprises a pair of channel sections 13 which in the side elevational view are shown to taper from the mast toward the free ends thereof. The base sections 13 have their wider flanged end portions curved upwardly as at 14, whose free edges engage beneath a side flange of the I-beam 15 which is cut away at the base of the beam for assembly of the base sections therewith. Upper and lower reinforcing plates 16 and 17 lap the base sections and mast beam at the joint, and are rigidly secured thereto as by welding.

The base sections 13, as shown in the top plan view, Fig. 6, diverge away from the mast 11 to points substantially distant therefrom and from which points the sections continue in parallel relation as at 18, thereby providing a relatively wide frame structure for supporting a motor or the like in a manner later referred to. The rigid base and mast structure is readily transportable in the provision of a caster 19 at the front end of each base or frame section 13. A third caster 20 has a swivel connection 21 at the lower bevelled end of the beam 15 which is provided with a flange 22 in continuation of the outer side flange of the beam thereby providing proper support for the caster 20.

The boom 12 comprises a pair of channel sections 24 which taper toward their free ends in both side and top views, and these sections as well as the base sections 13 have their opposing channels facing outwardly of the vertical center plane of the crane. The channel sections 24 have their base walls 25 in uniform spaced relation, as is clearly indicated in Figs. 4 and 6, for a purpose later to appear. The sections 24 are of substantial width adjacent the mast beam 15, and such sections curve downwardly as at 26 in the provision of substantial depth of the sections adjacent the mast beam 15.

The two sections 24 are of substantially greater combined width than the beam 15 and they are outwardly recessed from the center vertical plane thereof to provide walls 27 laterally displaced from the walls 25 for slidable engagement with the edges of the side flanges of the mast beam 15. The forward flange of the beam is slidably engaged by the forward end of the recess, and the rear ends of the sections 24 are turned inwardly as at 28 for slidable engagement with the rear flange of the beam 15.

The boom sections 24 are preferably interconnected by suitable means such as plates 30 welded to their upper and lower flanges whereby to hold the sections as a rigid boom unit. Thus, it will be seen that the boom 12 by the provision of the construction of its rear enlarged end as above described is vertically slidably supported on the mast beam 15.

A windlass 31 is rigidly supported on the rear flange of the mast beam 15, and which comprises an open top box-like support 32 connected by block 33 to the beam 15 and which block is disposed between the guide flanges 28 of the boom sections 24. Rotatably supported in the support 32 is a cable drum 34 which is driven by a worm gear 35 fixed on the drum shaft 35' and a worm 36 carried by shaft 36' meshes with the worm gear 35. A worm operating handle 37 is provided with several rectangular apertures 37' for selective engagement with a squared end of shaft 36' for provision of suitable variable torques.

A cable C having a substantial length thereof wound on drum 34 extends upwardly along the rear flange of the mast beam 15 and thence over horizontally spaced pulleys 38 and 39 rotatably supported in a frame 40 rigidly secured to the upper end of the mast beam 15 by means of the lap joint construction 40'. The cable continues from pulley 39 downwardly along the front flange of beam 15 and thence under a pulley 41 rotatably supported between the base walls 25 of sections 24, and the cable continues from the pulley 41 between the spaced walls 25 and thence extends over a pulley 42 rotatably supported between the walls 25 at the free ends of the boom sections 24.

A plate 43 is secured to the lower flanges of the sections 24 and is provided with an aperture through which the cable C freely extends but which precludes passage of the swivel hook 44 connected to the free end of the cable. The plate 43 cooperates with plates 30 in maintaining the boom sections 24 rigidly interconnected. In order to preclude binding between the boom 12 and the mast 11 a pair of upper rollers 45 and a like pair of lower rollers 46 are rotatably supported by the walls 27 of sections 24, the first pair of rollers engaging the front flange of the beam 15 and the second pair of rollers engaging the rear flange of the beam. From the foregoing it will be observed that the mast 11 provides laterally spaced slideways engaged by rollers supported by one end of the boom.

The invention comprises means for holding the boom 12 against downward movement on the mast 11 and for holding the cable C against movement relative to the boom. Such means, in a preferred embodiment thereof, comprises an elongated block 48 disposed between and suitably secured to the walls 25 of the boom sections 24 and such block is provided with opposed wedge walls 49. Also disposed between the walls 25 and suitably secured thereto is a second block 50 provided with a cylindrical recess 51 whose open end is disposed adjacent a suitable plate 52, secured to one of the side flanges of the I-beam 15 in vertical position and having a plurality of suitably spaced circular apertures 53 corresponding in diameter to that of the recess 51.

The cable C extends through the block 48 and between a pair of clamping jaws 54 which have wedge walls 55 cooperating with the walls 49. The jaws 54 extend outwardly of the block 48 and have floating pivotal connections 56 with a pair of lever arms 57 whose upper ends are pivotally connected at 58 to the walls 25.

The lower ends of lever arms 57 are pivotally connected at 59 to an end of a link 60 having a right angular extension 61 on its opposite end. A second and similar link 62 is provided with a right angular end extension 63 facing oppositely to the extension 61, the links being in laterally spaced relation at the region of said extensions.

The opposite end of the link 62 is provided with a lengthwise slot 64 in which is disposed a pivot pin 65 carried by one end of a stem 66 which extends through an aperture 67 at the base of the recess 51 and is provided with a latch bolt 68 disposed within the block recess 51 which is provided with an end adjacent plate 52 upwardly and inwardly bevelled, as indicated at 69. A coil spring 69 is disposed within the recess 51 in encircling relation to the stem 66 with its opposed ends engaging the bottom of recess 51 and the adjacent end of the latch bolt 68.

An operating handle 69 includes an elongated end member 70 disposed between links 60, 62 and

pivotedly connected intermediate its ends as at 71 to the walls 25, the opposite ends of member 70 having pivotal connections 71 with the link extensions 61, 63. The handle 69 extends from between the boom section walls 25 to a position beneath the boom and is provided with an actuating knob 72. The combined boom holding and cable clamping means is illustrated in full lines in Fig. 7, wherein the cable C is clamped against movement relative to the boom 12, wherein the latch bolt 67 is withdrawn from an aperture 53 in the plate 52. These operations are effected by movement of handle 69 toward the free end of the boom and in which movement, member 70 moves links 60, 62 slightly toward each other in a lengthwise direction. The link 60 pivots arms 57 in a direction to force jaws 54 into clamping engagement with the cable C, the link 62 withdrawing the latch bolt 67 from within one of the apertures 53.

Upon swinging the handle 69 toward the mast 11 into the position indicated by dotted lines in Fig. 7 and in full lines in Fig. 1, the cable C is released by the jaws 54 and the latch bolt 67 moves into contact with plate 52 for engagement with an aperture 53 when the block recess 51 becomes aligned therewith. The slot 64 in link 62 provides for movement of latch bolt 67 through camming action of the bevelled end 68 with the edge of an aperture 53 against the action of spring 69 when the cable is unclamped and when the hook 44 engages the plate 43 for raising of the boom. It is to be noted that the pivots 71 are disposed on opposite sides of a line parallel to the axis of stem 66 and extending through the pivot 71 whereby the spring 69 maintains the cable in clamped position through a toggle action.

From the foregoing, it will be apparent that the improved crane is relatively light in weight, thereby adapting it to ready movement from place to place by pushing the same through handles 73 secured to or unitary with the windlass support 32, the casters 19 and 20 providing for either straight line or angular movement of the crane along a floor. Notwithstanding such lightness, the crane is strong and capable of withstanding heavy loads, as well as rugged use.

The base 10 is preferably provided with a removable pan for supporting a motor or the like for transportation from one point to another, and such pan is disposed immediately below the cable hook 44, as will be apparent in Fig. 6. The pan preferably comprises a pair of L-sections 74 having a block 75 carried thereby, the block being provided with a recess defined by the opposed angular walls 76. The sections 74 are provided with hooks 77 on their opposite ends for engagement over the base sections 18 and the rearmost hooks are preferably provided with slots 78 for removably receiving pins 79 on sections 18, which pins restrain movement of the pan down the sloped forward end of the base.

In operation of the crane, it may be positioned with the base 10 which is substantially longer than the boom 12 disposed with its forepart beneath a motor or other object to be raised, with or without the pan in position. The boom is positioned at the most convenient altitude on the mast and so retained by the latch bolt 67. Should it be desired to raise the boom to a higher position on the mast, the knob 72 is grasped and the handle 69 moved to the full line position of Fig. 7 wherein the cable is clamped to the boom and the latch bolt 67 retracted. Upon rotation of the windlass worm 36 and consequent rotation of

the drum 34 the boom will be raised by the cable C and upon release of the cable by moving handle 69 in the opposite direction the latch bolt 67 will snap into the next adjacent aperture 53 below the axis of the latch bolt.

While the latch bolt 67 will permit upward movement of the boom in either position of the handle 69, it is necessary that it be withdrawn as in Fig. 7 when it is desired to lower the boom. 10 With the boom positioned in a desirable position, the cable is moved by windlass 31 to spring the hook 44 into adjacency to the object to be lifted. Upon engagement of the object by the hook the windlass is operated and the cable moved with a 15 resulting lifting of the object. Should it be desired to lift the object to a height greater than that at which the boom may be positioned, the hook 44 will engage the plate 43 and lift the boom with the object, the latch bolt 67 riding into 20 and out of the successive apertures 53 against the action of spring 69. It is to be noted at this point that the cooperating worm gear 35 and worm 36, while providing for movement of the cable upon actuating of the handle 37, act as a 25 lock against reverse movement of the gear and worm whereby a load being lifted will be retained thereby.

While I have disclosed my invention in accordance with a single specific structural embodiment thereof, it is to be understood that changes may be made which fairly fall within the scope of the appended claims.

What I claim is:

1. A portable lifting device comprising a caster supported base, a mast upstanding from the base, said mast having laterally spaced slideways extending vertically from the base, a horizontal boom having a slide at one end thereof engaging the spaced slideways of the mast, retractile 25 latch means between the mast and boom operative to hold the latter against downward movement while permitting upward movement thereof, a windlass fixed to said mast, a pulley adjacent the upper end of the mast, a pair of pulleys 40 mounted on the boom, one adjacent the slide and the other adjacent the free end of the boom, a cable extending from the windlass over the said respective pulleys and depending from the free end of the boom, interlocking means between the boom and the cable adjacent the inner end of the boom, and connecting means at the free end of the cable for engagement with the load, whereby a load may be moved to and from the boom or the boom moved to and from the base by the 45 cable.

2. A portable hoist and load transporting device comprising a caster supported base having a load support, a mast upstanding from the base, a boom slidably mounted on the mast and extending 50 from one side thereof over the base for movements relative thereto, manually releasable latch means between the mast and boom for restraining downward movement of the boom while permitting upward movement thereof, a windlass 55 mounted on the opposite side of the mast, a pulley adjacent the upper end of the mast, a pair of pulleys mounted on the boom, one adjacent the inner and one adjacent the outer end thereof, a cable extending from the windlass over the 60 said respective pulleys and depending from the outer end of the boom, and manually operable clamp means supported by the boom for restraining movement of the cable relative to the pulleys on the boom.

3. A portable crane comprising a vertically

disposed mast formed of an I-beam section, a base supporting the lower end of the mast and formed of a pair of laterally spaced channel sections having corresponding ends thereof rigidly secured to the lower end of the I-beam section adjacent one of the two parallel sides thereof, and a boom formed of a pair of channel sections with corresponding ends thereof slidably supported on the mast.

4. A portable crane according to claim 3 wherein in the boom channel sections at said corresponding ends are recessed in the provision of a guide slidably receiving the side flanges of the I-beam section.

5. A portable crane according to claim 3 wherein the base walls of the boom sections are in spaced relation providing a channel therebetween, a windlass supported on the rear flange of the I-beam section, a pulley rotatably supported on the upper end of the I-beam section, a pair of pulleys rotatably supported by said base walls between the boom sections, and a cable extending from the windlass and successively engaging said pulleys and extending from one of said pair of pulleys to a position beneath the free end of the boom and having a hook on the free end thereof.

6. A portable crane according to claim 3 wherein said base extends substantially beyond said boom, and a removable load support carried between and by said base channel sections beneath the free end of the boom.

7. A portable crane comprising a caster supported base, a mast of I-beam formation extending upwardly from one end of the base with its flanges fore and aft of the crane, a boom slidably supported by the mast and including opposed walls slidably engaged with opposed edges of the flanges of the I-beam and in spaced relation to the web thereof, the boom including spaced walls defining a channel therebetween extending from the mast to the free end of the boom, a windlass supported by the aft flange of the I-beam section, a pulley supported by the upper end of the mast, a pair of pulleys supported by said walls and disposed in said channel, a cable extending from said windlass and extending successively over said pulleys with the free end thereof depending from the free end of the boom, releasable latch means for retaining the boom in selected adjusted positions on the mast, and clamp means for locking the cable to the boom.

8. The structure according to claim 7 wherein said latch means and cable clamp means are disposed in said channel, and a handle operatively connected to the latch means and cable clamp means accessible beneath the boom and operative to simultaneously actuate both of said means.

9. A portable crane comprising a caster supported base, a mast rising from one end of the base, and a boom disposed above the base and having one end thereof slidably engaged with the mast, a windlass supported on the mast, a pulley at the upper end of the mast, a pair of pulleys supported by the boom, a cable extending from the windlass over the respective pulleys and depending from the outer end of the boom, a plate connected with the mast and having a series of vertically spaced apertures therein, the boom including a pair of spaced sections defining a channel therebetween, a pair of blocks supported in said channel with the cable extending through one of the blocks, normally retractible

clamping jaws disposed in said one of the blocks, a spring urged latch bolt slidably disposed in the other of said blocks for normal engagement within one of said apertures, a handle pivotally connected to said boom sections and depending from beneath the boom, and operative connections between the handle and the clamping jaws and the latch bolt for simultaneously moving the jaws to cable clamping position and for retracting the latch bolt from engagement with the plate aperture.

10. A portable crane according to claim 9 wherein said connections comprise a pair of links pivotally connected to an elongated member on the handle with the pivotal connections on opposite sides of the pivotal connection of the handle, said link pivotal connections being on opposite sides of a line parallel to the axis of the latch bolt and passing through the handle pivotal connection in the operative position of the handle, whereby providing a toggle connection for maintaining the cable in clamped position.

11. A portable crane according to claim 9 wherein said windlass comprises a drum connected to a shaft, a worm gear on the shaft, a worm carried by a shaft at right angles to the first shaft and cooperating with said worm gear, and an actuating handle provided with spaced apertures for selectively receiving the second named shaft.

12. A derrick comprising a wheeled chassis having a winding drum mounted thereon; a mast supported by said chassis and extending upwardly therefrom; a pulley mounted on the upper end of said mast; a boom slidably mounted on said mast and extending substantially horizontally therefrom at a level beneath said pulley; means for securing said boom against sliding movement relative to said mast at a selected vertical position of the boom; a second pulley mounted on said boom at one end thereof adjacent to said mast; a third pulley mounted on said boom at the other end thereof; a cable extending from said winding drum and engaging said pulleys in the order stated; hoisting means at the end of the cable beyond said third pulley; and engaging means on the boom adapted to engage said hoisting means to prevent movement of said cable relatively to said boom, whereby said boom may be moved to a desired vertical position with respect to said mast by said cable and winding drum when said hoisting means is engaged with said engaging means on the boom and the boom is released from the mast, and the hoisting means, cable and winding drum may be used to hoist objects when the boom is secured against sliding movement.
